PACKAGING MECHANISM

John Wayne Thomas, New Kensington, Pa., assignor to Aluminum Company of America, Pittsburgh, Pa., a corporation of Pennsylvania

Application June 18, 1936, Serial No. 85,957

25 Claims. (Cl. 226—85)

This invention relates generally to the art of packaging, and is particularly directed to mechanisms employed in applying closures to receptacles and the like.

- 5 The mechanisms hereinafter described have numerous applications in the closure and packaging art, and the invention is only limited in its applicability as defined in the claims appended hereto.
- 10 The invention contemplates the application of closures to receptacles and finds satisfactory employment in mechanisms associated with receptacle or bottle-filling devices, as well as in association with instrumentalities designed for the 15 purpose of manufacturing and applying closures in one and the same machine. Likewise, the invention has been successfully employed in the application of closures to receptacles where receptacles, having preformed closures loosely applied to their open ends, are presented to the 20 mechanisms of the invention from widely separated points in a packaging industry for the purpose of having their closures sealed thereto.

An object of the invention is the provision of 25 a mechanism for sealing closures on receptacles, such as bottles or the like, with a minimum amount of distortion of the closures.

Another object of the invention is to provide, in organized mechanisms, closure-applying instrumentalities in unitary construction which 30 permit their embodiment in a variety of packaging mechanisms.

A further object of the invention is to provide 35 a closure-applying device suitable for incorporation in packaging mechanisms of the continuous type wherein the receptacles to be sealed are presented in uninterrupted flow.

Other objects will present themselves on consideration of the following specification and 40 claims, wherein selected mechanisms incorporating the features of the invention are clearly and specifically described.

Referring to the drawings:

Figure 1 represents, in top plan view, a closure-forming, embossing, and applying or sealing mechanism, illustrating the relative location of the various units entering into the construction of a package or closure-sealing mechanism in which the preferred embodiment of the invention 50 is incorporated;

Figure 2 represents a side elevation of the mechanism illustrated in Figure 1;

Figure 3 represents a fragmentary view, to enlarged scale, taken along the line III—III of Figure 1, parts of the structure being broken away

to more clearly show the mode of construction of the mechanism;

Figure 4 represents a sectional plan view taken along the line IV—IV of Figure 3;

Figure 5 represents a sectional plan view taken 5 along the line V—V of Figure 3;

Figure 6 represents a fragmentary sectional elevation, to an enlarged scale, taken along the line VI—VI of Figure 5, illustrating the relative positions of the elements of a single closure-sealing device or head prior to the performance of a closure-sealing operation;

Figure 7 represents a fragmentary sectional elevation similar to that represented in Figure 6, the elements of the closure-sealing device being 15 illustrated in their relative positions following a closure-sealing operation;

Figure 8 represents a top plan view of the segmental ring element of the closure-sealing device illustrated in Figures 6 and 7;

Figure 9 represents a sectional elevation taken 20 along the line IX—IX of Figure 8;

Figure 10 represents a top plan view of the side-pressure sealing annulus of the closure-sealing device illustrated in Figures 6 and 7;

Figure 11 represents, in partial sectional elevation, the segment-actuating element removed from the closure-sealing device illustrated in Figures 6 and 7;

Figure 12 represents, in side elevation, the 30 pressure-actuating, cooperating element removed from the closure-sealing device illustrated in Figures 6 and 7;

Figure 13 represents a fragmentary sectional view, to an enlarged scale, of the cap transfer 35 mechanism incorporated in the mechanism illustrated in Figure 1;

Figure 14 represents a fragmentary, partial sectional elevation through a pair of adjacent receptacle-supporting pedestals taken along the 40 line XIV—XIV of Figure 3;

Figure 15 represents a fragmentary top plan view of the receptacle-raising cam mechanism;

Figure 16 represents a fragmentary front elevational view taken in the direction of the arrows XVI—XVI in Figure 15;

Figure 17 represents a partial top plan view, in partial section, of a modified embodiment of the mechanism illustrated in Figure 5;

Figure 18 represents a fragmentary sectional 50 plan view, to an enlarged scale, of the mechanism illustrated in Figure 17, parts being removed to more clearly illustrate the internal structure of the modified form of closure-sealing device;

Figure 19 represents a fragmentary sectional

elevation, to an enlarged scale, taken along the line XIX—XIX of Figure 17;

5 Figure 20 represents a sectional elevation, to an enlarged scale, taken along the line XX—XX of Figure 17;

Figure 25 represents a sectional plan view taken 20 along the line XXV—XXV of Figure 24.

In the preferred form of the invention, illustrated in Figures 1 to 16 inclusive, a self-contained or unitary closure-making and applying mechanism is shown which is readily adaptable to various types of standard filling and packaging devices. Since filling equipment, such as standard types of milk bottle fillers and other analogous machines, are familiar to those versed in this art, it has not been deemed necessary to illustrate the various and sundry types of apparatus susceptible of association with the present invention. Furthermore, the invention is possible of clear description and explanation without reference to its numerous applications.

35 Referring in more particularity to the preferred embodiment of the invention, Figures 1 and 2 disclose, in top plan and side elevational views, a unitary closure-making and applying mechanism incorporating the new and improved features and combinations of elements constituting the invention herein. A main frame or base member 10 supports the various elements of the mechanism and permits unitary movement and adaptation of the mechanism to various coordinated installations. Supported and suitably attached to the main frame 10 is a bracket or standard 11 (Figures 2, 3, and 5) upon the top surface of which is mounted a sub-press housing represented in its entirety by the reference numeral 12. In combination with the sub-press housing 12 are the various elements and coordinated instrumentalities for manufacturing closures or caps for subsequent application and sealing upon receptacles.

50 In the particular mechanism illustrated in Figures 1 to 16 inclusive, the closure-manufacturing instrumentalities are designed for the purpose of making metallic foil closures such as are used in the capping of milk bottles. Examples 55 of these closures are described and claimed in United States Letters Patents 1,796,728 and 1,796,729, but it will be quite manifest from a further consideration of the specification that the invention is not limited to these specific forms of closures.

55 The housing 12 has associated therewith a sub-press unit 14 and an embossing unit 15, shown to best advantage in Figure 2, wherein metallic foil, or other suitable material, drawn from a supply roll 16 mounted upon a suitable bracket 17, is first blanked and drawn into the form of shallow closures, which may thereafter be embossed with any desirable advertising or identifying subject matter between suitable dies mounted 60 in the unit 15. Typical closure-forming and embossing instrumentalities, as represented herein at 14 and 15, have been made the subject matter of United States Letters Patent to John E. Sharp and Max M. Kipfer, 1,963,103, issued under date of June 19, 1934, and 2,096,346, issued under date 65 of October 19, 1937.

65 The closures which have been drawn and embossed at 14 and 15, respectively, are suitably automatically discharged by way of a chute 18 (Figures 1 and 2) where they fall, under the influence of gravity, into position within a cap transfer mechanism represented in its entirety at 20 (Figures 1 and 13), a plurality of yieldable members in the form of rollers 19, incorporated in the cap transfer 20, cooperating with a moving 70 filled receptacle to loosely apply a closure thereto in the course of the mechanism's operation prior to presenting a receptacle, and its loosely applied closure, to the closure-sealing mechanism to be hereinafter described.

70 Referring now to the particular form of closure-sealing mechanism incorporated in the preferred embodiment of the invention, particular reference is made to Figures 3 to 12 inclusive. In Figure 5 a top plan view is illustrated in partial section, disclosing the preferred closure-sealing mechanism and its associated parts. Therein a suitable housing 22, in the form of a casting or plate, is slidably mounted upon a vertical shaft 24 (Figure 3). The plate 22 is provided with a downwardly extending, flanged hub 25 having a housing 28 attached and secured thereto as by means of cap screws 27. The housing 28 encloses and engages a nut member 29 in threaded engagement with the shaft 24 as at 30, 75 the periphery of the nut being constructed in the form of a worm wheel 31. A worm 32 is suitably journalled within the housing 28 in mesh with the worm wheel 31, a washer 33 secured to the extending end 34 of the worm 32 and a spring 35 interposed the housing 28 and washer 33 providing a restraining force against unintended rotation of the worm and worm wheel, as by vibration or the like. By means of a suitable crank handle, not shown, attached to the end 34 of the worm 32, the sealing head plate 22 may be raised or lowered into adjusted position to adapt the closure-sealing heads or devices to various bottle heights, and in order that the sealing head plate 22 will remain in proper registry with the receptacle supports immediately below the same 80 a key 36 is secured within the hub 25 in slidable engagement within the keyway 37 provided in the shaft 24.

85 The particular mechanism illustrated as the preferred form of the invention is represented as containing six separate sealing heads or devices, each represented in its entirety by the reference numeral 38 (Figures 3, 6, and 7). Since the six sealing heads contained in the plate 22 are identical in all respects, one of these sealing devices will be described in detail. Each sealing head comprises a top-pressure block-supporting member 41 adjustably mounted within an aperture in the plate 22, which is provided with suitable threads 40, and a lock nut 42, threaded upon the extending shank of the top-pressure block-supporting member 41, in contact with the top surface of the plate 22, secures the member 41 in any desired adjusted position within a counter-bored recess 39 within the plate 22.

90 Slidably mounted upon a shouldered portion 45, extending downwardly into the recess 39, is an externally threaded annular bolt member 46 having provided within peripheral portions there-

of diametrically opposed semi-circular apertures 47 which, in combination with similarly disposed semi-circular apertures in the plate 22, receive the unthreaded shanks 48 of shouldered bolts 43. The shouldered bolts 43 are threadedly engaged within threaded apertures 44 located at diametrically opposite points in the plate 22 in registry with the aforementioned semi-circular apertures. In threaded engagement with said bolt member 46 is an internally threaded nut member 49 which, as shown to best advantage in Figures 3, 5, 6, 7, and 11, is formed with an extending clevis 50 for the purpose of receiving a suitable cam roller 51.

The nut member 49 is maintained in a horizontal position through its bearing contact at 52 with the plate 22 and its bearing contact at 53 with a bottom apertured cover plate member 54, adjacent cover plate members 54 being secured in assembled relationship with the plate 22 through the medium of the flanged knurled heads of bolts 55 extending through the plate 22 and provided on the upper surface of plate 22 with clamping nuts 56 (Figure 3).

A chamfered annular member 57 is secured, as by means of a press fit, within a counterbored cavity 58 provided in the bolt member 46. This member 57 receives, in bearing contact with its chamfered surface 59, complementary chamfered surfaces of segments 60, which segments form an annulus of substantially channel form in cross section, as shown to best advantage in Figures 8 and 9. The annular channel 61 formed by the plurality of separate spaced segments 60 receives a side-pressure member 62 of rubber or other suitable plastic or deformable material, a pin 63 fixed within each of the segments 60 being received within complementary cavities or apertures 64 within the periphery of the side-pressure ring 62, which construction insures maintenance of the side-pressure ring 62 within its channel 61 and maintains the separate segments 60 in equally spaced relationship therewith. Also, the side-pressure annulus 62 is radially slotted, as at 65, for a purpose to be hereinafter explained.

A top annular pressure member 66 of suitable plastic material, such as rubber or the like, is also provided and is secured by means of an integral peripheral flange 67 extending within an undercut cavity in the top-pressure block-supporting member 41. As previously described, the top-pressure block member is adjustably positioned within the recess 39.

The segments 60 are slidably supported upon a suitable bearing washer 68 of hardened steel or the like which is held in bearing relationship with the bottom surface of the aforementioned segments through the medium of an apertured spanner nut 69 in threaded engagement at 70 with the bottom cover plate 54. The spanner nut 69 supports the elements of a sealing device in proper cooperative operating relationship with respect to the necessary clearance between the aforementioned bearing washer 68 and the segments 60, the purpose of which will be hereinafter described.

A disc member 73, the integral stem 74 of which extends vertically through a central aperture 75 in the stem of the top-pressure block-supporting member 41, functions in a manner to apply a downward pressure upon a closure supported upon a receptacle to be sealed. This downward pressure is resiliently applied through the medium of the spring 76, a cotter pin 77 or the like con-

trolling the downward vertical movement of the disc member 73.

Mounted upon the aforementioned vertical shaft 24, which supports the sealing head plate 22, and directly below the plate 22, is a member 5 in the form of a casting 78 provided with bearing bosses 79 equal in number and in registry with the aforementioned sealing heads 38. The casting 78 (Figure 3) is suitably keyed for rotation with the shaft 24 in registry with the aforementioned 10 plate 22, and within the bosses 79 pedestal members 80 are resiliently supported. Each pedestal comprises a bottle-supporting surface having a stem 81 which is connected to a sleeve member 82 mounted in sliding contact with a bushing 83 15 within the boss 79. The connection between the stem 81 and sleeve member 82 comprises a through pin 98 fixed in the stem 81 and having its extending end portions slidably engaged within suitable slots 84 in the sleeve 82. A suitable 20 coil spring 85 within a central counterbored portion of the stem 81 and in bearing relationship at its lower end with the closed bottom 86 of sleeve 82 provides a resilient support for the pedestal 25 80, vertical movement of the bearing surface of the pedestal, relative to the sleeve 82, being represented by the travel of the pin 98 within the slots 84.

Adjacent the lower end of each bearing boss 79 a member in the form of an apertured casting 30 88 is supported as by means of cap screws 87 (Figures 3 and 14). The casting 88 is constructed with a clevis 89 as an integral part thereof, and within the clevis is pivotally attached one end of a link member 90. The opposite end of the link 35 member 90 is pivotally connected through a second link member 91 and clevis 92 to the closed end of the sleeve 82. Rotatably mounted between the ends of link member 90 is a cam roller 93 which is positioned for rolling engagement upon 40 an arcuate cam member 94 (Figures 3, 14, 15, and 16).

The cam member 94 is so constructed that the pedestals 80, through the cooperation of the link-mounted cam rollers 93, are raised towards 45 the sealing devices or heads 38, during each revolution of the shaft 24, for the purpose of advancing receptacles, loosely supporting closures on their open ends, into the closure-sealing devices. Also, by means of an extending shaft 95, 50 supporting each cam roller 93, and a rail bracket 96 adapted to engage the shaft 95 (Figures 3, 15, and 16), return of the pedestals 80 to their lower receptacle-charging and discharging position is insured. Each pedestal unit, comprising 55 the sleeve 82 with its attached link member 90, cam roller 93, spring 85, and pedestal 80, is otherwise of sufficient dead weight to maintain the pedestals 80 in their lowered bottle-receiving and discharge positions, positive lifting of 60 the pedestals being accomplished through the medium of the arcuate cam 94, as aforescribed. The link mounting of the cam rollers 93 (Figure 14) by pivoting the link 90 adjacent the lower side of one pedestal-supporting boss 79, 65 and link-connecting the opposite end of the link member 90 to the sleeve member 82 within an immediately adjacent boss 79 provides a direct vertical lifting force on the pedestals and insures against undue wear and possible binding 70 such as would arise if an obliquely applied lifting force were resorted to. Furthermore, the resilient mounting of the pedestals 80, through the medium of springs 85, insures against receptacle breakage because of any inaccuracy in re- 75

ceptacle heights, and also insures a predetermined top-pressure within the sealing heads 38.

Although it is not essential for a complete understanding of this mechanism to fully describe the means for actuating the same, reference is made to Figures 1, 2, 3, and 5, wherein a motor 100, through suitable sprocket and chain connections 101, imparts rotary movement to the worm wheel 102 secured to the shaft 24, whereby shaft 24 is actuated. Through the same drive and the sprockets and chain indicated at 103, the feed and discharge starwheels 104 and 105, respectively, are driven in correctly timed relationship with respect to the plate 22 and pedestals 80, whereby bottles supplied to the starwheel 104 from a bottle-filling mechanism, not shown, or from any suitable supply of filled bottles, are carried through the mechanism for the purpose of having caps or closures secured to their open ends. Through intermeshing miter gears 107 and 108, motor 100 likewise drives the vertical shaft 109 which constitutes a drive for the various instrumentalities making up the cap-forming and cap-embossing units 14 and 15, respectively. It will be understood that the unitary drive and the various associated elements constituting the same are operated in correct timed relationship through the proper selection of the number of teeth in the various gears and sprockets making up the same; but since this drive is susceptible to numerous arrangements of parts, it has not been deemed necessary to fully describe this portion of the mechanism in further detail than that given hereinabove.

As shown to best advantage in Figures 3 and 5, the aforementioned bracket 11, which supports the sub-press 12 and its correlated parts, is semi-circular in form adjacent the motor, or right-hand side of the mechanism. Substantially centrally located towards the top of this semi-circular portion of the bracket 11 is an aperture 110 through which extend hollow bosses 111 formed integral with a plate member 112, the plate being supported, as by cap screws 113, on the rear face of the bracket 11. Four bosses 111 are provided in the preferred form of the construction under consideration, and shouldered bolts 114 extending through the bosses 111 threadedly engage at 115 a cam plate 116, a clearance being provided between the bosses 111 and the rear face of the cam plate 116 as at 117. The bolts 114 are each provided with a flange 118 which shoulders against the interior bottom wall of the hollow bosses 111, and a stiff spring 119 is disposed between the aforementioned flange 118 and an adjustable nut or cap member 120 which is threaded into the boss 111. The clearance 117 between the bosses 111 and the rear face of the cam plate 116, together with the back-up spring 119 and adjustable capping piece 120, provides a resilient and adjustable mounting for the cam plate, the purpose of which will be hereinafter understood.

In the operation of the preferred form of the invention heretofore described and illustrated in Figures 1 to 16 inclusive, filled bottles or other receptacles to be sealed are supplied from a filler or any other suitable source, as by a conveyor or the like, not shown, to the continuously rotating in-feed starwheel 104 which carries the filled receptacles beneath the closure transfer 20 (Figures 1 and 13), where closures or seals 121 are automatically loosely positioned upon the open ends of receptacles 122. Without interruption in the travel of the bottles

now having caps loosely supported thereon, the starwheel 104, in combination with suitable guide means, discharges the bottles centrally upon the pedestals 80 carried within the casting member 78, the pedestals being in their lowered position 5 as heretofore described. As illustrated to best advantage in Figure 5, the pedestals are rotated continuously in a counter-clockwise direction through the medium of their supporting casting 18, mounted upon the shaft 24, which direction 10 of rotation presents the cam wheels 51 in contact with the cam plate 116. When thus presented, the receptacles 122, with their loosely applied closures 121, have been raised into sealing position within the throat 123 (Figure 6) of 15 the particular capping head 38 whose cam wheel 51 is in contact with the cam plate 116. The raising of the receptacle into the position shown in Figure 6 is accomplished in proper timed relationship with respect to the coincidence of 20 the sealing head 38 with the cam plate 116 through the medium of the arcuate cam 94, as heretofore described.

Through the contact of the cam wheel 51 with the cam plate 116, the member 49 is oscillated 25 from right to left, as viewed in Figure 5, said oscillation taking place against the tension provided by springs 124.

Movement of the member 49 is confined to a horizontal plane in view of its mounting between 30 the bearing surfaces 52 and 53, and in view of the internal quick pitch acme thread 125 in the member 49, the threadedly engaging bolt member 46 reciprocally descends from the position shown in Figure 6 to that shown in Figure 7. 35 The descent of the member 46 reacts to carry the chamfered bearing ring 57 downwardly upon the chamfered surfaces of the segments 60, which latter carry the side-pressure sealing annulus 62. The annulus 62 is thereby compressed against the 40 depending skirt of the closure 121 to mold the same into conformity with the bottle finish directly in contact therewith, thereby performing a sealing operation. In this operation the radial slots 65 in the annulus 62 assist in the contraction of the annulus. 45

The top-pressure member 66 within the member 41 affords a plastic or elastic pressure upon the top surface of the closure 121, and the resiliently supported disc member 73 serves to position the closure 121 flatly upon the open end of its supporting receptacle prior to a sealing operation. 50

On completion of the travel of the cam wheel 51 in contact with the cam plate 116, the springs 124 return the member 49 to the position illustrated in Figure 6, wherein the bolt member 46 is returned to its upper position, and the elastic side-pressure member 62 returns the segments 60 to their expanded position. Movement of the bolt member 46 in response to oscillatory movement of its threadedly engaged nut member 49 is confined to movement in a vertical plane in view of the engagement of the bolt member 46 with the unthreaded shanks 48 of bolts 43 within the aperture 47 as hereinbefore described. The receptacles 122 are thereafter continuously discharged from the pedestals 80, which have been lowered through the medium of the aforementioned shaft 95 in engagement with bracket 96 70 (Figures 3, 15, and 16), by means of the continuously operating discharge starwheel 105, from which position they may be carried, as by a conveyor or the like, not shown, to any suitable destination. 75

The aforescribed resilient mounting of the cam plate 116 permits the application of a uniform sealing pressure during the sealing of a receptacle and guards against breakage of bottles through inaccuracies in a receptacle finish or variations in the lengths of the roller-supporting clevises 50. Likewise, the depth of the cam surface 116 and the adjustable mounting features of the plate 22, supporting the individual sealing heads or devices 38, provide a mechanism which may be adjusted to take care of various heights of receptacles, such as quarts, pints, half-pints, etc.

By reference to Figure 5 illustrating the preferred embodiment of the invention, and in particularity the directional arrows of rotation appearing thereon, it will be manifest that the mechanism hereinabove described is a left-hand machine. Obviously, the mechanism may be operated as a right-hand machine by reversing the direction of rotation from that indicated in Figure 5, in which case the relative positions of the arcuate cam 94 and bracket 96 (Figures 15 and 16) would be changed so that the bracket 96 would be located adjacent the opposite end of the cam 94 from that illustrated in Figure 15. An opposite hand machine to that described and illustrated herein would also necessarily require a reversal of the threaded connection between elements 46 and 49 of the sealing heads and essential changes in the drive to accommodate for the reversed direction of rotation of various other elements entering into the construction of the mechanism.

In another embodiment of the invention which has been illustrated in Figures 17 through 23, sealing devices represented in their entirety by the reference numeral 127 are mounted within a plate 128 which is supported upon a vertical shaft 129 for continuous rotary movement therewith, as in the preferred form of the invention. Each sealing head 127 comprises a centrally disposed top-pressure block 130, the shank 131 of which threadedly engages a threaded aperture 132 in the plate 128, a spanner nut 133 engaging the extending end of the shank 131 providing means for locking the top-pressure block 130 in any suitable adjusted position within a cavity 134. Immediately below the pressure block 130 a plurality of segments 135 are provided, each of said segments having a keyway 136 on its under side in engagement with an upstanding protuberance or key 137 formed integral, or otherwise, with a bottom plate member 138. Adjacent bottom plates 138 are secured to the plate 128 by means of T-bolts 139, extending through the plate 128 and provided with lock nuts 140.

The segments 135 are constructed to present a channel cavity 141 for the purpose of receiving a side-pressure annulus 142 of rubber or other suitable elastic or compressible material. This member is similar in all respects to that shown in Figure 10. Also, an annulus 143 is carried within a suitable receiving cavity in the top-pressure member 130. Surrounding the segments 135 in each of the sealing heads 127 is a segment-actuating annulus 144 which is concentrically guided through the medium of the cylindrical bearing surfaces 145 and 146, and top and bottom bearing surfaces 147 and 148, respectively. Each annulus is formed with an undercut portion 149, the vertical wall of which comprises a plurality of arcuate configurations 150 equal in number to the number of segments 135 within this undercut portion. The outer peripheral edges of the

segments 135 are likewise formed with arcuate surfaces 151 complementary to the previously mentioned surfaces 150. This construction presents a plurality of engaging complementary bearing surfaces which, on oscillation of the segment-actuating member 144 in a horizontal clockwise direction, advance the segments 135, which are oscillatably stationary relative to the oscillatory movement of the member 144 towards the center of the sealing device or head.

Each of the segment-actuating annuli 144 is equipped with an extending arm in the form of a clevis 152 within which a cam roller 153 is adjustably and rotatably mounted. Each cam roller is suitably provided with a bushing 154 and is rotatably mounted upon a spindle or axle member 155 (Figures 20 and 23). The spindles 155 are provided with a threaded portion 156 for threaded engagement at 157 with a threaded aperture in one fork of the clevis 152, and a concentric bearing portion 158 for bearing engagement within the opposite fork of the clevis 152. Intermediate the threaded portion 156 and bearing portion 158 an eccentric portion 159 is provided for receiving and supporting the cam wheel or roller 153. This construction permits radial adjustment of the cam roller 153 with respect to the center of the segment-actuating annulus 144 through the medium of the threaded connection 157 and lock nut 160, it being only necessary to rotate the spindle 155 in its threaded connection 157 with the clevis 152 to change the position of the eccentric bearing portion 159 rotatably supporting the cam roller 153.

As in the preferred embodiment of the invention, a cam plate 161 is suitably mounted in the path of rotation of the sealing head supporting plate 128, whereby the cam rollers 153 come in contact with the cam plate 161 to oscillate the segment-contracting annulus 144 in a horizontal clockwise direction against the tension of springs 162. The cam plate 161 in this embodiment of the invention is preferably resiliently mounted with respect to the cams 153, as in the preferred form of the invention illustrated in Figure 3. The oscillation of the annulus 144 contracts the segments 135, which in turn contract the side-pressure sealing ring 142, a receptacle 163, having a cap 164 loosely supported thereon and raised into the throat 165 (Figure 20) of the sealing head, having its closure sealed to its receptacle through this operation. The top-pressure annulus 143 serves to provide a compressible cushion against the top surface of the closure 164, and a resiliently mounted disc member, similar to that incorporated in the preferred form of the invention and identified at 73 therein, may be provided for flatly positioning the closure upon its receptacle.

A third embodiment of the invention is illustrated in Figures 24 and 25. In this embodiment, a single sealing head mechanism is disclosed as distinguished from the multiple sealing head devices described and illustrated previously hereto.

The mechanism in this embodiment is somewhat similar to that illustrated in Figures 17 through 23, in that the sealing head or device represented in its entirety by the numeral 168 is equipped with an oscillatably mounted annulus 169 suitably supported for movement in a horizontal plane within the sealing device. The annulus 169 is concentrically supported, with respect to the vertical axis of the device, through the medium of the cylindrical bearing at 170.

A bottom plate 171, secured in place as by means of the studs 172, supports a plurality of segments 173, the outer peripheral edge of said segments being arcuate in form, as at 174. The segments 173 are provided on their under side with keyways 175 into which project keys 176, or similar protuberances, formed integral with the top surface of the bottom plate 171. The annulus 169 has a second annulus 178 secured thereto, as by rivets 179, the second annulus extending downwardly into bearing relationship with the upper surface of plate 171 and encasing the peripheral arcuate edges of the segments 173. The vertical interior wall 180 of the annulus 178, adjacent the arcuate edges of the segments 173, is constructed in the form of complementary arcuate surfaces 181 which are in bearing contact with the arcuate edges 174 of segments 173. Oscillatory movement of the annulus 169, relative to the segments 173, in a clockwise direction as viewed in Figure 25 and indicated by the dotted line construction therein, radially advances the segments 173 towards the center of the sealing head.

Extending laterally from the annulus 169 is a lever arm 182 having an abutment 183 thereon. This abutment is arranged to bear upon an adjustable stud 184 which is threadedly mounted within a block member 185 slidably mounted in a clevis member 186 supported within an extending bearing or housing 187 formed integral with a shaft-enclosing stationary housing 188 constituting a part of the sealing mechanism. The bearing 187 is suitably provided with a bushing 189. The clevis member 186 is provided, at its extremity opposite to that in which is supported the stud 184, with a rotatably mounted cam wheel 190.

Within the housing 188 is mounted a main driving shaft 191 of this single sealing head machine. This shaft is driven from any suitable source of power, not shown, and is preferably driven continuously in the operation of this embodiment of the invention. Secured to the shaft 191 is a cam 192 upon the surface of which the cam wheel 190 rides. The cam 192 is provided with a protuberance 193, which, on anti-clockwise direction of rotation of the shaft 191, raises the cam wheel 190 and slide block 185 towards the right, as viewed in Figure 25, such movement causing the annulus 169, together with the arcuately constructed annulus 178, to move in a clockwise direction to radially contract the segments 173. A suitable tension spring 194, secured to the laterally extending arm 182, by means of the cap screw 195, and affixed at its opposite end to the stationary stud 196, provides a tension, against which stress the cam 192 and its associated elements act. Preferably the stud-carrying block 185 is seated upon a compression spring 197 which affords means for applying a resilient pressure through the medium of the cam 192.

Within an annular channel 198 formed in the segments 173 is a side-pressure annulus 199 of rubber or other suitable compressible material which on contraction of the aforementioned segments 173 reacts to conform the skirt of a closure loosely supported upon a receptacle and positioned within the sealing head into close conformity with the glass finish supporting the closure. As in the previously described mechanisms, a top-pressure annulus 200 is likewise provided in this form of the invention, as is also a centrally positioned and resiliently mounted flanged member 201 which serves to position a

closure flatly in contact with the top surface of its supporting receptacle prior to a sealing operation.

In the operation of this embodiment of the invention it will be seen that the sealing head functions to compress the skirt of a closure into sealing relationship with the closure-supporting receptacle once during each revolution of the shaft 191 and its cam 192. In this form of the invention, receptacles having closures loosely supported thereon are presented in registry beneath the throat 202 of the sealing head, which device is adapted to be lowered into contact with the receptacle-supported closure in contradistinction to the previous embodiments of the invention wherein the receptacles were raised into the sealing heads. As in the previously described embodiments of the invention, the side-pressure ring 199 also acts, on relief of the pressure applied thereto through the segments 173 and annulus 169, to expand the segments to their normal open position, whereby the sealing head may be raised above the sealed receptacle. Various mechanisms are available for the presentation of filled receptacles to a capping machine of the type described herein, and the reciprocation of the sealing head may be attained through a cam and link mechanism, not shown, suitably mounted upon the main shaft 191 of the machine.

The oscillatably actuated means for contracting the compressible closure-applying medium is common to all three embodiments of the invention herein, and it is this feature of the invention that makes it possible to incorporate this general type of sealing head in a continuously operated machine of the rotary type. This is considered of paramount importance in high speed packing and sealing of receptacles and has made the invention widely adaptable to numerous types of continuous capping mechanisms.

Having thus described and explained the invention and its mode of operation, it is to be understood that the particular embodiments of the invention were selected merely for purposes of illustration and that variations in the form and arrangement of elements shown and described therein may be made without departing from the nature and scope of the invention except as defined in the claims appended hereto.

What I claim is:

1. A mechanism of the class described, comprising a sealing head provided with means adapted to be radially contracted to conform a closure skirt with a receptacle finish, horizontal oscillatable means for applying substantially uniform radial pressure to said first-mentioned means to contract the same, and adjustable means in cooperation with said horizontal oscillatable means adapted to control and insure a predetermined contracting pressure in said sealing head.

2. A mechanism of the class described, comprising a sealing head provided with a compressible member adapted to be radially contracted to compress a closure skirt into conformity with a receptacle finish, horizontal oscillatable means for applying substantially uniform radial pressure to said compressible member to contract the same, and adjustable means in cooperation with said horizontal oscillatable means adapted to control and insure a predetermined contracting pressure in said sealing head.

3. A mechanism of the class described, comprising a sealing head provided with a compressible top-pressure means and a compressible side-

pressure means, means for positioning a receptacle having a closure loosely supported thereon in resilient contact with said top-pressure means, horizontal oscillatable means for applying substantially uniform radial pressure to said side-pressure means to compress the skirt of the closure into conformity with the glass finish of the receptacle, and adjustable means in cooperation with said horizontal oscillatable means adapted to control and insure a predetermined contracting pressure in said sealing head.

5. A mechanism of the class described, comprising a sealing head provided with a compressible member adapted to be radially contracted to compress a closure skirt into conformity with a receptacle finish, adjustable horizontal oscillatable means for contracting said compressible member, and adjustable means in cooperation with said horizontal oscillatable means adapted to control and insure a predetermined contracting pressure in said sealing head.

10. A closure-sealing mechanism comprising a compressible side-pressure member adapted to compress the skirt of a closure into close conformity with a receptacle finish, a segmental annulus in engagement with said compressible member, said segmental annulus having an inclined bearing surface, an annulus having a complementary inclined surface in bearing relationship with said first-mentioned inclined surface, an exteriorly threaded member engaging said second-mentioned annulus, and an interiorly threaded oscillatable member in threaded engagement with said exteriorly threaded member, said interiorly threaded member being adapted to be horizontally oscillated whereby the exteriorly threaded member is advanced to contract the segmental annulus and compress said compressible member.

15. A mechanism of the class described, comprising a sealing head provided with a compressible top-pressure means and a compressible side-pressure means, means for positioning a receptacle having a closure loosely supported thereon in resilient contact with said top-pressure means, adjustable horizontal oscillatable means for contracting said side-pressure means to compress the skirt of the closure into conformity with the glass finish of the receptacle, and adjustable means in cooperation with said horizontal oscillatable means adapted to control and insure a predetermined contracting pressure in said sealing head.

20. A closure-sealing mechanism comprising a compressible side-pressure member adapted to compress the skirt of a closure into close conformity with a receptacle finish, a segmental annulus in engagement with said compressible member, said segmental annulus having an inclined bearing surface, an annulus having a complementary inclined surface in bearing relationship with said first-mentioned inclined surface, an exteriorly threaded member engaging said second-mentioned annulus, and an interiorly threaded oscillatable member in threaded engagement with said exteriorly threaded member, said interiorly threaded member being adapted to be horizontally oscillated whereby the exteriorly threaded member is advanced to contract the segmental annulus and compress said compressible member.

25. A mechanism of the class described, comprising a sealing head provided with a compressible member adapted to be radially contracted to compress a closure skirt into conformity with a receptacle finish, a segmental ring engaging said compressible member, horizontal oscillatable means in association with the segmental ring for applying substantially uniform radial pressure to said compressible member, and adjustable means in cooperation with said horizontal oscillatable means adapted to control and insure a predetermined contracting pressure in said sealing head.

30. A closure-sealing mechanism comprising a compressible side-pressure member adapted to compress the skirt of a closure into close conformity with a receptacle finish, a segmental annulus in engagement with said compressible member, said segmental annulus having an inclined bearing surface, an annulus having a complementary inclined surface in bearing relationship with said first-mentioned inclined surface, an exteriorly threaded member engaging said second-mentioned annulus, and an adjustable interiorly threaded oscillatable member in threaded engagement with said exteriorly threaded member, said interiorly threaded member being adapted to be horizontally oscillated whereby the exteriorly threaded member is advanced to contract the segmental annulus and compress said compressible member.

35. A mechanism of the class described, comprising a sealing head provided with a compressible member adapted to be radially contracted to compress a closure skirt into conformity with a receptacle finish, means associated with said compressible member and adapted to be oscillated in a horizontal plane to apply radial pressure to said compressible member to contract the same, and a cam member adapted to actuate said oscillatable means, said cam member incorporating adjustable means for controlling and insuring a predetermined contracting pressure in said sealing head.

40. A mechanism of the class described, comprising a sealing head provided with a compressible side-pressure means adapted to be radially contracted to compress a closure skirt into conformity with a receptacle finish, a plurality of segments engaging said compressible means, horizontal means associated with said segments, a cam roller supported by said horizontal means, and a resiliently mounted cam member adapted to engage said cam roller and to oscillate said horizontal means into engagement with said segments to radially contract the same, said cam member incorporating adjustable means for controlling and insuring a predetermined contracting pressure in said sealing head.

45. A mechanism of the class described, comprising a sealing head provided with a compressible member adapted to be radially contracted to compress a closure skirt into conformity with a receptacle finish, a plurality of sealing devices, supported in registry with a plu-

5. A mechanism of the class described, comprising a sealing head provided with a compressible member adapted to be radially contracted to compress a closure skirt into conformity with a receptacle finish, adjustable horizontal oscillatable means for contracting said compressible member, and adjustable means in cooperation with said horizontal oscillatable means adapted to control and insure a predetermined contracting pressure in said sealing head.

10. A mechanism of the class described, comprising a sealing head provided with a compressible top-pressure means and a compressible side-pressure means, means for positioning a receptacle having a closure loosely supported thereon in resilient contact with said top-pressure means, adjustable horizontal oscillatable means for contracting said side-pressure means to compress the skirt of the closure into conformity with the glass finish of the receptacle, and adjustable means in cooperation with said horizontal oscillatable means adapted to control and insure a predetermined contracting pressure in said sealing head.

15. A mechanism of the class described, comprising a sealing head provided with a compressible top-pressure means and a compressible side-pressure means, means for positioning a receptacle having a closure loosely supported thereon in resilient contact with said top-pressure means, adjustable horizontal oscillatable means for contracting said side-pressure means to compress the skirt of the closure into conformity with the glass finish of the receptacle, and adjustable means in cooperation with said horizontal oscillatable means adapted to control and insure a predetermined contracting pressure in said sealing head.

20. A mechanism of the class described, comprising a sealing head provided with a compressible member adapted to be radially contracted to compress a closure skirt into conformity with a receptacle finish, a segmental ring engaging said compressible member, horizontal oscillatable means in association with the segmental ring for applying substantially uniform radial pressure to said compressible member, and adjustable means in cooperation with said horizontal oscillatable means adapted to control and insure a predetermined contracting pressure in said sealing head.

25. A mechanism of the class described, comprising a sealing head provided with a compressible member adapted to be radially contracted to compress a closure skirt into conformity with a receptacle finish, a segmental ring engaging said compressible member, adjustable horizontal oscillatable means in association with the segmental ring for contracting said compressible member, and adjustable means in cooperation with said horizontal oscillatable means adapted to control and insure a predetermined contracting pressure in said sealing head.

30. A mechanism of the class described, comprising a sealing head provided with a compressible side-pressure means adapted to be radially contracted to compress a closure skirt into conformity with a receptacle finish, a plurality of segments engaging said compressible means, horizontal means associated with said segments, a cam roller supported by said horizontal means, and a resiliently mounted cam member adapted to engage said cam roller and to oscillate said horizontal means into engagement with said segments to radially contract the same, said cam member incorporating adjustable means for controlling and insuring a predetermined contracting pressure in said sealing head.

35. A mechanism of the class described, comprising a sealing head provided with a compressible member adapted to be radially contracted to compress a closure skirt into conformity with a receptacle finish, a plurality of sealing devices, supported in registry with a plu-

- rality of receptacle pedestals, said sealing devices and pedestals being adapted to rotate in fixed relationship, a compressible side-pressure member in each sealing device, horizontal oscillatable means associated with each side-pressure member, cam rollers carried by each horizontal oscillatable means, a cam plate in the path of rotation of said cam rollers, said cam rollers on contact with said cam plate being adapted to 5 horizontally oscillate said oscillatable means to apply radial pressure to said compressible side-pressure members to contract the same and means for raising receptacles positioned on said pedestals, and loosely supporting closures thereon, into the sealing devices prior to contracting said side-pressure members, said cam plate incorporating adjustable means for controlling and insuring a predetermined contracting pressure in 10 said sealing head.
15. A mechanism of the class described, comprising a sealing head provided with a top and side compressible means, a plurality of segments in engagement with said side-pressure means, said segments being arcuate in form on their outer periphery, a horizontal member surrounding said segments, said horizontal member having an interior wall composed of arcuate surfaces equal in number and complementary with the arcuate form of the segments, said horizontal member being adapted to be oscillated relative to the segments to radially contract the side compressible means in a closure-applying operation, and adjustable means in cooperation with said horizontal oscillatable member adapted to control 25 and insure a predetermined contracting pressure in said sealing head during a closure-applying operation.
20. 16. A mechanism of the class described, comprising a sealing head provided with a side-pressure means for compressing a closure skirt into conformity with a receptacle finish, means in said head for resiliently pressing the closure flatly upon its receptacle, means for advancing said receptacle and loosely supported closure into said sealing head, horizontal oscillatable means for applying substantially uniform radial pressure to said side-pressure means in a closure-applying operation, and adjustable means in cooperation with said horizontal oscillatable means adapted 30 to control and insure a predetermined contracting pressure in said sealing head.
25. 17. In a continuous closure-applying mechanism, means for supplying receptacles having closures loosely supported thereon beneath a sealing head, means in said sealing head for compressing the skirt of a closure into conformity with a receptacle finish, means for raising the receptacle and closure into the sealing head, and horizontal oscillatable means for contracting said skirt-compressing means, said horizontal oscillatable means being resiliently retractable on completion of a closure-applying operation and incorporating adjustable means for controlling and insuring a predetermined contracting pressure in 35 said sealing head.
30. 18. In a sealing mechanism, a compressible member adapted to engage and compress a closure skirt into close conformity with a receptacle finish for securing the closure thereon, cam-operated means associated with said compressible member for applying radial pressure thereto to contract the same during a compressing operation, and an adjustable resiliently mounted cam plate adapted to contact with said cam-operated means during a compressing operation,

said resilient mounting permitting adjustment of the cam-operated means for any inaccuracies in receptacle finish.

19. In a sealing mechanism, a top compressible member and a side compressible member adapted to engage and compress a closure top and skirt respectively into conformity with a receptacle finish, a plurality of segments engaging and supporting said side member, said segments having arcuate outer peripheries, an annulus surrounding said segments, said annulus having arcuate surfaces normally in partial bearing engagement with the arcuate peripheries of the segments, a clevis connected to said annulus and extending outwardly therefrom, a cam roller rotatably mounted in said clevis, and a cam plate, relative movement between said clevis and said cam plate being adapted to bring the cam roller into bearing contact with the cam plate, and said bearing contact being adapted to oscillate the annulus into complete arcuate bearing relationship with said segments, whereby the segments are radially contracted to compress said closure skirt into close conformity with the receptacle finish.

20. In a mechanism for making and applying closures to filled receptacles, means for continuously presenting filled receptacles to a continuously rotating closure-sealing member, a plurality of sealing heads within said closure-sealing member, a plurality of receptacle pedestals arranged below and in registry with said sealing heads, a cam member for raising said pedestals towards the sealing heads to position the receptacles within said sealing heads, horizontal oscillatable means for applying substantially uniform radial pressure to a closure on said receptacles to compress said closure while positioned within the sealing heads, means for positively returning the pedestals from their raised position following a closure-sealing operation, and adjustable means in cooperation with said horizontal oscillatable means adapted to control and insure a predetermined contracting pressure in said sealing head.

21. A mechanism of the character described, comprising closure-making and embossing units, means for positioning a closure discharged from the aforementioned units upon a receptacle while the same is in motion, a continuously rotating closure-sealing member, a plurality of sealing heads within said member, a plurality of receptacle-receiving pedestals supported below said closure-sealing member and adapted to rotate in registry with said sealing heads, an arcuate cam member for raising said pedestals towards said sealing heads to present receptacles carried thereon within said sealing heads during a portion of a revolution of the closure-sealing heads and pedestals, horizontal oscillatable means for applying substantially uniform radial pressure to a closure on a receptacle to compress said closure while the receptacle is in its raised position within a sealing head, means in combination with the arcuate cam member for positively lowering the pedestals to withdraw the sealed receptacles from the sealing heads during another portion of a revolution of the sealing heads and pedestals, and adjustable means in cooperation with said horizontal oscillatable means adapted to control and insure a predetermined contracting pressure in said sealing head.

22. In a mechanism of the class described, a sealing head member including a plurality of individual sealing heads, compressible means within each sealing head to compress a closure into conformity with a receptacle supporting said closure,

5 a sealing head actuating member for each sealing head extending outwardly beyond the sealing head member and adapted to compress said compressible means by application of radial pressure thereto, a 10 cam plate positioned to contact with said extending actuating members, said extending actuating members being adapted to be oscillated through striking the cam plate on rotation of the sealing head member, and adjustable means in cooperation with said sealing head actuating members and cam plate whereby a predetermined pressure is exerted in each sealing head.

15 23. In a mechanism of the class described, a sealing head member including a plurality of individual sealing heads, a compressible member within each sealing head adapted to compress a closure into conformity with a receptacle supporting said closure, oscillatory means associated with each compressible member and adapted to compress said compressible member by application 20 of radial pressure thereto, said oscillatory means being disposed to project outwardly beyond said sealing head member, and a cam plate member adjustably mounted in a fixed position relative to said sealing head member, said cam plate being 25 in the rotary path of said sealing head member, said oscillatory means being adapted to strike

said cam plate on rotation of the sealing head member to successively compress said compressible members.

24. A mechanism of the class described, comprising a sealing head provided with a compressible member adapted to be radially contracted to compress a closure skirt into conformity with a receptacle finish, adjustable oscillatable means for applying radial pressure to said compressible member to contract the same, and adjustable means in cooperation with said oscillatable means adapted to control and insure a predetermined contracting pressure in said sealing head.

25. A mechanism of the class described, comprising a sealing head provided with a compressible member adapted to be radially contracted to compress a closure skirt into conformity with a receptacle finish, adjustable oscillatable means adapted to be oscillated to apply radial pressure to said compressible member to contract the same, resilient means associated with said oscillatable means adapted to retract said oscillatable means, and adjustable means in cooperation with said oscillatable means adapted to control and insure a predetermined contracting pressure in said sealing head.

JOHN WAYNE THOMAS.
